By her Attorneys,

E. L. Gregory, Inventor

UNITED STATES PATENT OFFICE.

EMMA L. GREGORY, OF KOSCIUSKO, MISSISSIPPI.

FOLDING CRATE.

SPECIFICATION forming part of Letters Patent No. 654,061, dated July 17, 1900.

Application filed March 2, 1900, Serial No. 7,094. (No model.)

To all whom it may concern:

Be it known that I, EMMA L. GREGORY, a citizen of the United States, residing at Kosciusko, in the county of Attala and State of 5 Mississippi, have invented a new and useful Folding Crate, of which the following is a specification.

This invention relates to shipping-crates which are especially designed for shipping 10 poultry, and has for its object to provide an improved device of this character which may be folded or knocked down into compact form for return shipment. It is furthermore designed to provide an improved arrangement 15 of a drinking or feed receptacle which is fixedly connected to the crate, so as to be held against accidental displacement during transportation and also is located so as to be effectively housed and protected by the parts of 20 the crate in the folded position thereof.

With these and other objects in view the present invention consists in the combination and arrangement of parts, as will be hereinafter more fully described, shown in the accompanying drawings, and particularly pointed out in the appended claim, it being understood 25 that changes in the form, proportion, size, and minor details may be made within the scope of the claim without departing from 30 the spirit or sacrificing any of the advantages of the invention.

In the drawings, Figure 1 is a perspective view of a folding shipping-crate in its set-up or normal position and constructed according 35 to the present invention. Fig. 2 is a longitudinal sectional view thereof. Fig. 3 is a similar sectional view showing the crate in its folded or knocked-down position.

Corresponding parts in the several figures 40 of the drawings are designated by like characters of reference.

Referring to the accompanying drawings, 1 designates the bottom of the crate, which is of rectangular form and provided upon its 45 under side with transverse strips or cleats 2 to form shoulders upon which the crate is designed to rest for a purpose as will be hereinafter more fully described.

Secured to the upper side of the bottom and 50 extending flush with the opposite longitudinal edges thereof are the opposite strips 3, to

the upper faces of which are hingedly connected the respective side sections 4, which are foldable inwardly in opposite directions. The opposite end sections 5 are hinged directly to the upper side of the bottom, so as to fold inwardly and lie flat upon said bottom, as indicated in Fig. 3, and by reason of the strips 3 the side sections are elevated sufficiently to fold flat against the outer or upper 55 sides of the end sections. It will be observed that the combined length of either pair of opposite foldable sections is not equal to the length of the bottom piece in any direction, so that when the side sections are folded there 60 is a central exposed portion of the upper side of the bottom piece. I utilize this exposed portion of the bottom piece for the location of a receptacle 6, which is designed to hold water or feed for the poultry and is fixedly 65 connected to the bottom piece in any preferred manner, so that it may not become displaced during shipment.

In order that the foldable side sections may be fixedly connected in the normal or set-up 75 position of the crate, I provide a top 7 of substantially the same shape and dimensions as the bottom piece. Each side piece of the frame of the top is provided with a plurality of bolt-openings 8, preferably two, that are 80 adjacent to the respective opposite ends of the side, and said perforations or openings are designed to register with corresponding bolt-openings 9, formed through the top side of the respective foldable side sections to receive 85 the respective bolts 10, which have rounded or countersunk heads at the upper or outer side of the top, and nuts 11, provided at their opposite ends and bearing against the lower faces of the sides of the foldable 90 sections. The top is also provided with a centrally-located hinged door 12, which is disposed above the receptacle or pan 6 in order that the latter may be readily accessible for placing the feed or water therein. The depth 95 of the pan is such that when the sides are folded inwardly the outer faces thereof are above or outwardly beyond the upper edge of the pan, so that the top is immediately above the pan and the latter is effectively 100 housed and protected in the folded position of the crate.

When the side and end sections are folded inwardly, they expose bolt-openings 13, that are formed through the bottom piece and register with similar bolt-openings 14, formed in the ends of the foldable side sections, so that the respective fastening-bolts 10 may pass through these openings and project at the under side of the bottom piece for the reception of the nuts 11, whereby the parts of the crate are firmly held in their folded positions. It will now be seen that the cleats or shoulders 2 project outwardly beyond the ends of the bolts in the folded position of the crate in order that the latter may rest firmly upon another crate, and the bolts do not form projections or obstructions to prevent a compact and firm piling of a plurality of crates one upon the other.

It will be understood that the bars forming the frames of the end and side sections may be joined in any manner commonly known to carpenters and joiners and also the wire

screen material may be secured to such frames in any well-known or preferred manner.

What I claim is—

In a folding poultry-crate, the combination with a bottom, having a feed or water receptacle fixed centrally to the upper side thereof, of opposite side sections hinged to fold inwardly upon the upper side of the bottom and terminating short of the receptacle when the crate is folded, the upper faces of certain of the side sections being above the upper edge of the receptacle, and a removable top or cover to connect the side sections in the opposite positions thereof and to cover and protect the receptacle.

In testimony that I claim the foregoing as my own I have hereto affixed my signature in the presence of two witnesses.

EMMA L. GREGORY.
